UNITED STATES PATENT OFFICE.

GARDINER W. CHIPLEY, OF CHICAGO, ILLINOIS, ASSIGNOR OF ONE-HALF
TO CHARLES W. ARMBRUST, OF SAME PLACE.

RAILWAY BRAKE-SHOE.

SPECIFICATION forming part of Letters Patent No. 651,435, dated June 12, 1900.

Application filed January 18, 1900. Serial No. 1,871. (No model.)

To all whom it may concern:

Be it known that I, GARDINER W. CHIPLEY, a citizen of the United States of America, residing at Chicago, in the county of Cook, 5 in the State of Illinois, have invented a certain new and useful Improvement in Railway Brake-Shoes, of which the following is a description, reference being had to the accompanying drawings, forming a part of this 10 specification.

The first feature of my invention relates to the provision of a divided or two-part brake-shoe by which certain advantages hereinafter explained are attained, and its second feature relates to the provision of a brake-shoe 15 adapted to receive and have attached to it the back or rear portion of a partially-worn shoe, whereby partially-worn shoes may be used completely up by attaching them to and 20 using them with new shoes, as hereinafter explained.

In the accompanying drawings, Figure 1 is a middle longitudinal section of a plain cast-iron divided brake-shoe embodying the first 25 feature of my invention; Fig. 2, a corresponding view of a similar shoe embodying also the second feature of my invention; Fig. 3, a view corresponding to Fig. 2, showing a partially-worn shoe applied to the shoe of Fig. 30 2; Fig. 4, a perspective view of the two co-operating halves of a new and a partially-worn shoe, illustrating the manner of assembling the two and securing them together; and Fig. 5, a perspective view of the inner 35 or middle ends of the shoes shown in Fig. 4, also illustrating the manner of assembling and securing them together.

The same letters of reference are used to indicate corresponding parts in the several 40 views.

The two halves A B of the divided shoe (shown in Fig. 1) have plain wearing-faces *a a* and at their inner abutting ends are provided upon their backs with the two-part attaching-lug C, having the keyway *b*. The 45 shape of the lug C is shown in Figs. 4 and 5.

Upon their backs, near their outer ends, the two halves A B of the shoe are provided with the guide-lugs D D, adapted to be embraced 50 by the ends of the brake-head, and with the transverse lugs E E, adapted to face the ends

of the brake-head. Both sets of lugs will be hereinafter referred to as the "guide-lugs."

When the two halves A B of the shoe are placed together as in Fig. 1, their working- 55 faces *a a* lie in the arc of the same circle; but the abutting ends of the two halves of the shoe are preferably so shaped as not to abut flatly together throughout their adjacent faces, an outwardly-flaring open space 60 being left between the rear portions of said faces for the purpose of more readily permitting independent movement of the two halves of the shoe when attached to the brake-head.

As is well known in the practical use of 65 brake-shoes, the entire working face of the shoe is rarely pressed uniformly against the surface of the wheel when the brakes are set, owing to imperfect adjustments and to unequal wear upon the faces of the shoes. In 70 the use of solid or continuous shoes the shoe is practically fulcrumed upon the brake-head at its middle, where it is secured to the brake-head by the attaching-lug and key, with the result that when in setting the brakes one end 75 of the shoe is forced against the wheel before its opposite end contacts with the wheel the shoe is subjected to a strain which often breaks it after it has become worn and weakened. By forming the shoe in two separate 80 halves, as in Fig. 1, and permitting slight independent play of the two halves this objection to solid or continuous shoes is overcome, since the forcing of one half of the shoe against the wheel in advance of the other produces no strain upon the shoe. 85

Another advantage of the divided shoe is that when one half of the shoe becomes worn to a materially greater extent than the other, as very frequently happens in the use of 90 brake-shoes, such worn half may be removed and replaced by another less-worn half, thereby restoring the uniformity of the two halves of the shoe.

Fig. 2 and the succeeding figures of the 95 drawings illustrate the second feature of my invention. As there shown, the two halves A B of the shoe are provided at their abutting ends with a recess *c*, extending inward from the face of the shoe opposite the attaching-lug C on the back of the shoe, and projecting into each side of such recess from the 100

respective halves of the shoe are two lugs *d*. This recess *c* is adapted to receive the attaching-lug *C* upon the back of a worn shoe, Fig. 3, and the lugs *d* are adapted to enter the 5 keyway in such attaching-lug, and thereby lock the worn shoe to the new one. The two halves of the shoe are likewise provided near their outer ends with recesses *e*, extending inward from the face of the shoe and adapted 10 to receive the guide-lugs *D E* upon the back of the worn shoe, as shown in Fig. 3, and for the purpose of locking the ends of the worn shoe to the ends of the new shoe the lugs *E* upon the back of the shoe are provided upon 15 their outer faces with recesses *f*, adapted to be engaged by lugs *g*, projecting into the recesses *e* in the face of the shoe.

The back of the shoe is formed in an arc having the same radius as that of the face of 20 the shoe, so that the back of one shoe will fit the face of another shoe.

In assembling the parts each half of the worn shoe is applied to and interlocked with the corresponding half of the new shoe independently 25 of the opposite halves of the shoes, and when each half of the combined shoe has been thus assembled the two halves of the combined shoe are brought together end to end, as in Fig. 3, and then secured to the 30 brake-head.

Figs. 4 and 5 illustrate the manner of combining the respective halves of the new and old shoes, the face of the new shoe and its recesses and the back of the old shoe with 35 its projecting lugs being shown in Fig. 4. The back of the old shoe is placed against the face of the new shoe, with the attaching and guiding lugs in their recesses in the face of the new shoe, but with the outer end of the 40 new shoe projecting outwardly slightly beyond the end of the old shoe, and the latter is then slid outwardly along the face of the new shoe to cause the lugs *g* and *d* in the recesses in the face of the new shoe to engage 45 the recess *f* and keyway *b* in the lugs upon the back of the old shoe, and thereby lock the latter to the former, as will be readily understood.

A worn shoe of the style shown in Fig. 1 50 may be combined with a new shoe of the style shown in Fig. 2 as readily as can a worn shoe of the latter style, and in Fig. 3 it may be assumed that the worn shoe there shown is, in fact, the shoe of Fig. 1. Indeed, owing 55 to the fact that the shoe of Fig. 1 has an unbroken wearing-surface it will under some circumstances be found advantageous to employ the two styles of shoes together, the shoe of Fig. 2 serving as a means for completely 60 using up the worn shoes of the style shown in Fig. 1.

While I have illustrated and described in detail a simple and efficient method of attaching the worn shoes to the new ones by interlocking them together, my invention is not 65 restricted in its broader scope to this particular method and means of attaching the old

shoe to the new one, since, so far as I am aware, it has not heretofore been proposed to use up worn brake-shoes by attaching them 70 to new shoes in any manner whatsoever, and my invention therefore contemplates the employment of any suitable means for securing the old shoes to the new ones in the practical utilization of this idea.

It will be understood that my invention has nothing to do with the particular construction of the body of the shoe—*i. e.*, whether of solid cast metal or otherwise—or with the employment or non-employment of “inserts” in the 80 wearing-face of the shoe. Any of the various methods of constructing the body of the shoe and any of the usual inserts may be employed in connection with my invention without affecting the latter. It will also be understood that the second feature of my invention may be utilized in solid or continuous shoes, it being simply necessary for such purpose to provide suitable means for securing the old and new shoes together when assembled.

Having thus fully described my invention, I claim—

1. A brake-shoe composed of two independent halves abutting together on a transverse 95 line at the middle of the shoe and each provided with means for attaching it to the brake-head, substantially as described.

2. A brake-shoe composed of two independent halves separated from each other on a 100 transverse line at the middle of the shoe and each provided with a guiding-lug and with one-half of a two-part attaching-lug, substantially as described.

3. The herein-described divided brake-shoe, composed of the two halves *A B* separated from each other on a transverse line at the middle of the shoe and each provided with a guiding-lug *D E* and with one-half of a two-part attaching-lug *C* having a keyway 110 *b*, substantially as described.

4. A brake-shoe provided in its wearing-face with recesses adapted to receive the attaching and guide lugs upon the back of another shoe, substantially as described.

5. A brake-shoe provided in its wearing-face with recesses adapted to receive the guide and attaching lugs on the back of another shoe, and with means for securing the two shoes together, substantially as described.

6. A brake-shoe having its wearing-face and its back formed in parallel planes, so that the back of one shoe will fit the face of another shoe, and provided in its wearing-face with recesses adapted to receive the attaching and guide lugs upon the back of another shoe, substantially as described.

7. A two-part or divided brake-shoe, composed of two halves separated transversely at the middle of the shoe, and adapted to have 130 the back of another shoe secured to its face, substantially as described.

8. A two-part or divided brake-shoe, composed of two halves separated upon a trans-

verse middle line, and provided in its wearing-face with recesses adapted to receive the attaching and guide lugs upon the back of another shoe, substantially as described.

5 9. A two-part or divided brake-shoe, composed of two halves separated upon a transverse middle line, and provided in its wearing-face with recesses adapted to receive the attaching and guide lugs upon the back of another shoe and with means for securing the two shoes together, substantially as described.

10 10. A two-part or divided brake-shoe, composed of two halves separated upon a transverse middle line, and provided with recesses 15 in its wearing-face adapted to receive the attaching and guide lugs upon the back of another shoe, and with lugs projecting into said recesses and adapted to coöperate with the lugs upon the back of the other shoe to lock 20 the two shoes together, substantially as described.

11 11. A two-part or divided brake-shoe separated upon a transverse middle line and having its wearing-face and back formed in parallel planes, so that the back of one shoe will 25 fit the face of another shoe, and having its wearing-face provided with recesses adapted to receive the attaching and guide lugs upon the back of the other shoe, substantially as 30 described.

12. A two-part or divided brake-shoe separated upon a transverse middle line and having its wearing-face and back formed in parallel planes, so that the back of one shoe will fit the face of another shoe, and having its 35 wearing-face provided with recesses adapted to receive the attaching and guide lugs upon the back of the other shoe and with lugs projecting into such recesses and adapted to coöperate with the attaching and guide lugs 40 upon the back of the other shoe, substantially as described.

13. The herein-described two-part or divided brake-shoe, composed of the halves A B provided in their wearing-faces with the recesses c e and the lugs d g projecting into said recesses, and provided upon their backs with the attaching-lug C having the keyway b, and with the guide-lugs D E having the recesses f, substantially as and for the purpose specified. 45

14. A brake-shoe adapted to engage a wheel and composed of two independent substantially-like halves abutting together on a transverse line at the middle of the shoe, substantially as described. 55
